(57) **CLAIM**

The ornamental design for a football helmet air freshener, as shown and described.

DESCRIPTION

FIG. 1 is a top front perspective view of a football helmet air freshener showing our new design.

FIG. 2 is a top perspective view thereof.

FIG. 3 is a bottom perspective view thereof.

FIG. 4 is a front view thereof.

FIG. 5 is a back view thereof.

FIG. 6 is a right side view thereof; and,

FIG. 7 is a left side view thereof.

In FIGS. 1, 3, and 4, the broken lines depict portions of the football helmet air freshener, and form no part of the claimed design.

Portions of the drawings are shaded with stippling to indicate contrasting surfaces.
